UNITED STATES PATENT OFFICE.

GEORGE D. EIGHMIE, OF NEW YORK, N. Y.

EXPLOSIVE TURBINE-ENGINE.

1,187,515.

Specification of Letters Patent. Patented June 20, 1916.

Application filed May 27, 1915. Serial No. 30,722.

To all whom it may concern:

Be it known that I, GEORGE D. EIGHMIE, a citizen of the United States, residing at New York, in the county of New York and State of New York, have invented certain new and useful Improvements in Explosive Turbine-Engines, of which the following is a specification, reference being had therein to the accompanying drawing.

10 My present invention relates to certain new and useful improvements in explosive turbine engines.

15 The object is to provide a rotary motor of the turbine type which will effectively operate in consequence of the explosion of a gaseous mixture therein, but will be free from any complicated structural combinations, having only a few simple parts which are not likely to get out of order, and which 20 are related to each other in a durable and convenient form so as to develop large power in a comparatively small engine.

It consists essentially in the combination with a hollow shaft having inlet ports for introducing the explosive mixture to a turbine wheel, of such a wheel formed with a series of curved fan blades and an annular explosion chamber surrounding said fan, the outer rim of said chamber consisting of a 25 stationary cylindrical casing whose wall is formed with alternate solid and slotted segments, there being also another concentric cylindrical member surrounding the stationary casing, which latter member is also 30 made up of alternate solid and slotted segments, the slotted segments in the movable cylinder having their vanes reversely inclined to the vanes in the slotted segments 35 of the stationary cylinder, in order that the impact of the explosions within the explosion chamber may increase the pressure within said chamber and communicate motion to the revolving member and thereby 40 actuate the central main shaft; and the invention also comprises numerous details and 45 peculiarities in the construction, arrangement and combination of parts, substantially as will be hereinafter described and more fully set forth in the claims.

50 In the accompanying drawing illustrating my invention: Figure 1 is a vertical section of my improved rotary explosive turbine engine on the line 1, 1 of Fig. 2; Fig. 2 is a transverse section of the same on the line

2, 2 of Fig. 1; Fig. 3 is an enlarged detail view.

Similar characters of reference designate corresponding parts throughout the different figures of the drawing.

1 denotes the main horizontal shaft, which 60 is hollow and is provided at intervals, corresponding in number with the number of turbine wheels employed in the engine, with a series of inlet ports 2, by which the explosive mixture coming from any suitable carbureting or other source through the hollow shaft is directed into the interior of the turbine wheels.

There may be any number of turbine wheels applying their power to the same 70 central rotary shaft 1. I will now explain how each one of these wheels is constructed and arranged to operate. Each wheel consists of a narrow rotary cylinder or flanged disk 3 having a hub 4 bolted or otherwise 75 firmly secured at 5 to the shaft 1, and a second adjacent flanged disk 6 which is stationary, though having the shaft 1 passing through it with a ball bearing between them, and being securely bolted or otherwise fastened at its bottom pedestal 7 to a suitable foundation 8, there being a mixing or pressure chamber 9 between the two disks 3 and 6 into which the gas or explosive mixture passes from the inlet ports 2.

85 The revolving disk 3 is provided with a series of curved vanes or fan blades 10 of greater or less length which are preferably integral with the disk 3 and have a width substantially equal to the space between the 90 disks 3 and 6. These fan blades revolve rapidly and the suction created thereby draws the gas into the engine. The stationary disk 6 is provided at a point near the fan blades 10 with a cylindrical flange 11 95 having at various points in its length a number of openings 12, say, for example, three or more; when three, they being obviously 120 degrees apart. These openings lead into the explosion chamber 13, which is an annular chamber between the flange 11 of the stationary disk 6 and a similar cylindrical flange 14 on the outer periphery of disk 6. The revolving disk 3 has moreover the valve cover plates 15 consisting of projections on the face of the disk 3 integral therewith, which valves 15 have the function of closing the openings 12 at certain times

during the revolutions of the disk 3, and uncovering them at other times, the opening being for the purpose of allowing the explosive mixture to pass through ports 12 into the explosion chamber 13.

The encircling cylindrical flange 14 on the outer periphery of the stationary disk 6 consists of alternate solid and slotted segments. The solid segments 16 have no openings therein, while the slotted segments 17, consist of a series of parallel vanes or blades formed by parallel cuts in the flange 14 for the entire width thereof, and at right angles to the face of the disk 6 as shown clearly in Fig. 1, it being obvious that the blades 17 may be either straight or curved. Furthermore, the rotary disk 3 has its encircling cylindrical flange 18 similarly formed with solid segments 19 and intermediate segments 20, the latter consisting of a series of parallel vanes or blades made by cutting slots through the entire width of the flange 18 at this point similar to the segments 17. Thus it will be seen that just outside of the annular explosion chamber 13 there is a cylindrical stationary member 14 consisting of a series of alternate solid and slotted segments, immediately surrounding which and concentric therewith is a similar revolving cylindrical member consisting of a similar series of alternate solid and slotted sections. It should be noted, moreover, that the blades of the slotted sections 20 of the revolving member incline in a direction opposite to that of the vanes or blades of the slotted sections 17 of the stationary member, so that when the explosions occur successively within the explosion chamber 13 the force of the explosions will be directed by the inclined vanes 17 outwardly against the reversely-inclined vanes of the segments 20 of the revolving disk 3, thereby imparting a rotary motion to said disk, and consequently to the shaft 1 to which it is attached. In the explosion chamber 13, preferably at points opposite to the ports 12, are placed suitable spark plugs 21, the action of which is timed to correspond with the introduction of the charge so that the ignition may take place at the proper time in the revolution of the parts of the turbine wheels.

In order to indicate one way in which power may be taken off from the central hollow shaft 1, I have shown a pulley 22, affixed thereon at a point between the turbine wheels, there being in this example of the invention two wheels at each side of the pulley 22, around which pulley passes a suitable belt 23 leading off to any point where it is desired to apply the power.

In the foregoing description I have been speaking of a single wheel as an example only, and have stated there may be any number of wheels arranged in connection with the same shaft, each wheel, of course,

being made up of one revolving disk and one stationary disk. When there are several wheels, it will be convenient to place them so that two of the stationary disks 6 will be formed integral with each other, as shown at 24 (Fig. 2), two of the disks 6, therefore, having the same pedestal 7, and likewise the disks 3 of companion wheels will be located adjacent to each other, as shown at the center of Fig. 2. This is only one convenient form of placing the parts, and I do not wish to be confined thereto. It is also desirable that ball bearings 25 be placed between the shaft 1 and an inner circular hub portion of the stationary disk 6, or in the case of a pair of wheels the stationary connecting sleeve part 24 belonging to two disks 6, so that as the shaft 1 rotates, the ball bearings 25 may contribute to the ease and facility of the revolution.

The operation of my improved rotary explosive engine will be evident from the foregoing description of the construction and arrangement of the various mechanical details without the need of additional explanation. It will be observed that the ports 2 are always open to admit air and gas through the hollow shaft 1 into the interior chamber 9 in the wheel or wheels, where it will be drawn in by the suction of the fan blades 10. Immediately after the engine is started and the valves 15 are released from the ports 12, a charge of the explosive mixture will fill the explosion chamber 13 and at the proper moment, determined by the timing of the sparking devices, as spark plugs 21, the charge will be fired in the chamber 13 and will act through the vanes 17 against the vanes 20, causing the disk or disks 3 to rotate, carrying with them the central hollow shaft 1 and rotating the pulley 22, also driving belt 23, and so on, the exhaust after each explosion taking place between the vanes or blades 17 and 20 and into the outer air.

It will be noted that various changes in the precise structure of the several parts may be made without exceeding the scope of the invention or unfavorably affecting the value of the claims, and I, therefore, reserve the liberty of making all such changes as experience may prove to be wise and expedient.

Having thus described my invention, what I claim as new and desire to secure by Letters Patent, is:

1. In an internal combustion engine, a pair of disks arranged parallel to each other, one revolving and one stationary, the revolving disk carrying a series of fan blades and at its outer periphery a series of vanes, and the stationary disk provided with an apertured cylindrical flange surrounding the said fan blades and carrying also at its periphery a series of vanes which work in

conjunction with the vanes of the other disk, and valve means for allowing the explosive mixture to pass from the fan into the space between the apertured flange and the adjacent set of vanes.

5 2. In an internal combustion engine, a pair of disks, one revolving and one stationary, the revolving disk having peripheral vanes, groups of which alternate with solid flange sections, and the stationary disk having an apertured cylindrical flange and a peripheral series of vanes, groups of which alternate with solid flange sections, the vanes of the two disks coinciding with each 10 other at times in order to impart rotary motion to the revolving disk.

15 3. In a rotary explosive engine, the combination of a revolving disk having a peripheral cylindrical flange formed with vanes, and having also a series of fan blades, a stationary disk having a port-provided flange and a peripheral cylindrical flange formed with vanes, there being an explosion chamber between the latter and the 20 port-provided flange, and the peripheral vane-provided flanges of the disks being in working contact and valve means for allowing the explosive mixture to pass from the fan into the space adjacent to the vanes.

25 4. In a rotary turbine explosive motor, the combination of a revolving disk carrying a series of fan blades and having a peripheral cylindrical flange formed with alternate slotted and solid segments, a stationary disk having a cylindrical ported flange and at a distance therefrom on its outer edge a cylindrical flange formed with alternate solid and slotted segments, the peripheral flanges of the disks being in working contact and having their vanes coinciding with each other at times in order to impart rotary motion to the revolving disk, and valve means for introducing an explosive mixture through the ports of the ported flange into 30 the space between said flange and the adjacent vanes.

35 5. In a rotary explosive turbine motor, the combination of a revolving disk having a cylindrical peripheral flange formed with vanes, and also having a series of fan blades, a stationary disk having a cylindrical apertured flange, and at a distance therefrom a cylindrical peripheral flange formed with vanes, the space between said two flanges 40 forming an explosion chamber, means for covering the ports of the ported flange at times during the revolution of the revolving disk, and a central hollow shaft on which the revolving disk is mounted and through which the explosive mixture is introduced into the turbine.

45 6. In an explosive turbine motor, the combination of a central shaft having a series of inlet ports, a revolving disk secured on said shaft, and having a cylindrical flange

formed with solid portions and alternate slotted portions to provide vanes, a stationary disk having a cylindrical apertured flange, and at a distance therefrom another cylindrical flange formed with solid portions between which are slotted portions to provide vanes, the said vane-provided flanges of the two members being in operative contact, and the vanes of the one inclining in a direction opposite to that of the inclination 70 of the vanes of the other, a series of fan blades revolving with the revolving disk, covering devices operating in connection with the apertures in the apertured flange, and means for introducing the explosive mixture into the interior of the turbine.

7. In a rotary explosive engine, the combination of a revolving disk, having a plurality of series of vanes formed at intervals on the periphery with interposed solid flanges between said series of vanes, a stationary disk having similar vanes and solid flanges between them, said latter disk having also an apertured cylindrical flange adjacent to which is an explosion cylinder, and a central hollow shaft having a bearing in the stationary disk, and carrying the revolving disk, and provided with an inlet opening through which the mixture passing through the hollow shaft may enter the space between 90 the disks.

8. In a rotary explosive engine, the combination of a revolving disk having a peripheral cylindrical flange formed with vanes, and having also a series of fan blades, 100 and one or more valve projections, a stationary disk having a cylindrical apertured flange, and a peripheral cylindrical flange formed with vanes, there being an explosion chamber between it and the apertured flange, 105 ignition devices in said explosion chamber, and a hollow shaft having a bearing in the stationary disk and supporting the revolving disk, together with means whereby the shaft transmits power.

9. In a rotary explosive engine, the combination of a revolving disk having a cylindrical flange, sections of which are slotted to form groups of inclined vanes between which groups are solid sections of the flange, 115 a stationary disk having a cylindrical flange, sections of which are slotted to form inclined vanes between which groups the rest of the flange is left solid, the two cylindrical flanges being in contact with each other, and the inclination of the groups of vanes being opposite in the one to that in the other, all arranged so that during the revolution of the revolving disk its vanes may pass opposite to the vanes of the other disk and receive the explosive pressure, means for introducing the explosive mixture into the space contiguous to the aforesaid sets of vanes, and means for igniting said mixture.

10. In a rotary explosive motor, the com-

bination of a revolving disk having a cylindrical flange formed with groups of inclined vanes, between which are solid sections, and having also a series of curved fan blades 5 and one or more port covers, a stationary disk having a cylindrical apertured flange, whose apertures are covered at times by said port covers, and having at a distance from said flange a cylindrical peripheral 10 flange formed with groups of reversely in-

clined vanes, between which are solid sections, the space between said vane-provided flanges and the aforesaid apertured flange forming an explosion chamber, and means for admitting an explosive mixture into the 15 fan chamber from which it can pass into the explosion chamber, together with ignition means.

In testimony whereof I affix my signature.
GEORGE D. EIGHMIE.
